UNITED STATES PATENT OFFICE.

MORRIS STRAUSS, OF OMAHA, NEBRASKA, ASSIGNOR TO THE CUDAHY
PACKING COMPANY, OF SOUTH OMAHA, NEBRASKA.

DESIGN FOR A DISPLAY-STAND.

SPECIFICATION forming part of Design No. 32,075, dated January 2, 1900.

Application filed December 1, 1899. Serial No. 738,928. Term of patent 7 years.

To all whom it may concern:

Be it known that I, MORRIS STRAUSS, a citizen of the United States, residing at Omaha, in the county of Douglas and State of Nebraska, have invented and produced a certain new and original Design for a Display-Stand, of which the following is a specification.

My invention relates to a novel design for display-stands, and is illustrated in the accompanying drawing, in which the figure is an elevation.

As shown in the drawing, the leading or essential feature of my design consists of a tripod having depending chains supporting at their lower ends a pot containing a plurality of pigs, a portion of the bodies of which is exposed above the top of the pot.

In the said drawing the reference-numeral 1 indicates the tripod, consisting of three twisted rods curled inward at their bases, as at 3, and outward at their upper ends, as at 4, and formed intermediate their ends with ring-like circles 5.

6 indicates depending chains connected to the edge and supporting a pot 7. In the pot 25 are arranged a plurality of pigs 8, a portion of the body of each being exposed above the top of the pot. The pot has a convex bottom 9 when viewed externally.

10 indicates a centrally-pendent chain supporting a body 11.

My design presents an advertising device of novel, pleasing, and distinguished appearance.

Having thus described my invention, what 35 I claim as new, and desire to secure by Letters Patent, is—

The design for a display-stand essentially as herein shown and described.

In testimony whereof I have hereunto set 40 my hand in presence of two subscribing witnesses.

MORRIS STRAUSS.
